RECEPTACLE AND CLOSURE THEREFOR

William Lockhart, Cleveland, Ohio, assignor to
 Cornell Securities Corporation, Cleveland,
 Ohio, a corporation of Delaware

Application March 14, 1935, Serial No. 11,087

7 Claims. (CL 228-61)

My invention is an improvement in receptacles such as metallic barrels or shipping drums of the full removable head type and relates more particularly to a clamping ring and operating mechanism for removably securing the head or cover on the receptacle.

I am aware that heretofore expanding and/or contracting link and lever operated clamping rings have been devised and used to clamp a cover upon the open end of a metallic drum or other container. Such devices were first contributed to the art, so far as I am aware, by Vernon E. Cornell as illustrated in his Letters Patent Nos. 1,792,278, 1,792,279, 1,792,280 and 1,792,281 all dated February 10th, 1931.

The present invention is an improvement upon such devices and one of the objects thereof is to provide an operating mechanism for expanding and contracting the ring, which affords even greater ease of operation than those heretofore used.

Another object of the invention is to provide an operating lever fulcrumed about a pivot which is movable with respect to the ring or receptacle.

A further object is to provide a floating type of lever, that is, one pivotally connected through suitable links or their equivalents to the ends of the ring for expanding and/or contracting the ring.

Another object is to exert predetermined closing pressures on the drum and cover and to more uniformly distribute these pressures or forces throughout the extent of the ring.

Other objects and advantages of the invention will become more apparent from the following description of one embodiment thereof, reference being made to the accompanying drawing in which like reference characters are employed to designate like parts throughout the same.

In the drawing:—

Figure 1 is a top plan view of the clamping device in use;

Figure 2 is an enlarged section taken on line 2—2 of Figure 1;

Figure 3 is a fragmentary plan view of the ring showing the same in closed or contracted position to clamp the cover on the receptacle in sealed fluid tight relation;

Figure 4 is a view similar to that of Figure 3, but shows the ring in open or expanded position, as in removing the cover from the receptacle, and

Figure 5 is an elevation of the ring taken in the direction of the arrows on line 5—5 of Figure 3.

Referring now more particularly to the drawing, the barrel or drum is indicated at 1. The up-

per open end of the container is formed with a peripheral bead 2. A cover 3 comprising a cupped or depressed member, having a peripheral upwardly and outwardly extending flange 4, is supported by the bead 2 in such a manner that the cupped portion of the cover may be telescoped for a short distance within the open end of the container, as illustrated in Figure 2. It will be noted that a portion of the flange 4 is of arcuate cross section to conform with the approximate curvature of the upper surface of the bead. A packing 5 consisting of an annulus of any suitable packing material, such as flexible rubber tubing or cork, is interposed between the flange 4 and the bead. 10

According to the present invention, I have provided an extremely simple and efficient means for removably securing the cover on the receptacle or container to effect a fluid tight seal between the same by exerting a substantially uniform and firm pressure along the cover flange and bead in 20 a direction substantially parallel to the axis of the container.

Such means preferably includes a transversely split, channelled clamping ring 6 of substantially U-shaped cross-section and which is capable of 25 being contracted and expanded by suitable means. In the form illustrated the upper and lower flange and bead engaging walls respectively of the ring extend in substantially parallel planes and engage the cover flange and bead of the container to press 30 the same together tightly when the ring is contracted. However, it is to be understood that the ring and receptacle open end may be so designed that the cover will be pressed into a tight seal with a shoulder at the receptacle open end when 35 the ring is expanded.

Upon contracting the type of ring herein illustrated it will be seen that the cover flange will be tightly pressed against the packing 5 and the supporting bead 2 under a substantially vertical pressure. 40

The ring is provided at its ends with suitable lugs, plates, or the like, 7 and 8, which are preferably welded to the adjacent ring ends respectively and extend inwardly of the ring to movably support suitable means for contracting and expanding the ring. 45

A simple toggle connection is provided between the plates 7 and 8 and preferably consists of an operating lever 9 and a pair of links 10 and 11 connecting the lever with the plates 7 and 8 respectively. More specifically, the lever 9 consists of a stamping or forging curved to fit within the inner confines of the receptacle when the ring is contracted. The lever is pivotally connected at 50

one end with an end of the link 10 as at 9', the other end of the link 10 being pivotally connected with the plate 7 as at 12. The second link 11 pivotally connected at one end with the lever 9; as at 13, is pivotally connected at its other end with the plate 8 as at 14. It is preferred in practice to arrange the links 10 and 11 so that they will lie and operate in planes on opposite sides of the plane of the lever 9, thus permitting free overlapping of the same in operation, the conservation of materials, and more positive alignment of the ring ends during contraction of the ring.

The link 11 is formed with an outwardly inclined cam-like surface 15 which engages the upright annular wall of the cover flange as shown in Figures 1 and 3, when the ring is contracted. In this manner the ring is made to adjust itself on the drum so as to more uniformly distribute the sealing pressures around the cover and bead when the ring is contracted.

The lug or plate 7 may be formed with a latch comprising a depending flange 16 extending a short distance below the plane of the plate 7 to serve as a stop for the handle lever 9 when the same is in the position shown in Figure 3. As the handle closely approaches this position it is depressed toward the cover until it passes beneath the stop 16. When released it will abut the inner surface of the stop to hold the ring fully contracted. Registering openings 17 and 18 are formed in the latch and lever respectively to receive a wire seal when desired.

It is to be noted that by my invention a very simple locking or clamping device is easily provided. Its simplicity insures low cost of production, yet the device is extremely rugged and strong, and is remarkably easy to operate. This ease of operation is primarily due to the toggle arrangement wherein the lever is of the floating type, that is, it is not fixedly pivoted to one of the lugs but is floated on members connecting the lugs with the lever. Due to this arrangement also, the device becomes self-locking as the lever approaches its limit of movement to contract the ring. In so doing the pivot 9' passes a dead center line connecting the pivot points 13 and 14.

It is also to be noted that the operating mechanism may be selectively set or adjusted to vary the degree of contraction or expansion of the ring. This is accomplished by providing a reversed L-shaped slot 20 in the bracket 8 as indicated in Figures 1, 3 and 4, to receive the pin or pivot 14 of the link 11. This slot provides a plurality of sockets or seats 21 and 22 for this purpose and an imaginary straight line passing from the axis of the pin 12 through the axis of the pin 14, when seated in the socket 21, will define a chord of shorter length than such a line passing through the axis of the pin 14 when seated in the socket 22. Therefore the contraction and expansion of the ring may be selected conveniently. It is desirable in shipping the drums empty to lock the cover in place securely but not so firmly as to put a "set" in the gasket 5. Then when the drum is charged with material it is desirable to effect a maximum of closing pressure to obtain a fluid tight seal. By my invention these results are readily accomplished.

Various changes in the details of construction and arrangement of parts may be made without departing from the spirit of my invention or the scope of the appended claims.

I claim:

75 1. A clamping device for removably securing a

cover upon a barrel, said device comprising a split channeled ring, inwardly extending lugs adjacent the ends of the ring, and means for contracting and expanding the ring, said means including a link pivoted at one end to one of said lugs, an operating lever pivotally connected adjacent its end with the other end of said link, and a link pivotally connecting the other lug with another portion of said lever whereby said links will be caused to overlie one another and a portion of said lever when the ring is flexed to one of its extreme positions, but not when the ring is flexed in an opposite direction.

2. A clamping device for removably securing a cover upon a barrel, said device comprising a split channeled ring, inwardly extending lugs adjacent the ends of the ring, and means for contracting and expanding the ring, said means including a link pivoted at one end to one of said lugs, an operating lever pivotally connected adjacent its end with the other end of said link, and a member pivotally connecting the other lug with another portion of said lever, said connecting member being shaped to engage the cover of a receptacle in contracting the ring to exert a substantial pressure thereagainst.

3. A clamping device for removably securing a cover upon a barrel, said device comprising a split channeled ring, inwardly extending lugs adjacent the ends of the ring, and means for contracting and expanding the ring, said means including a link pivoted at one end to one of said lugs, an operating lever pivotally connected adjacent its end with the other end of said link, and a member pivotally connecting the other lug with another portion of said lever, said connecting member being shaped to engage the cover of a receptacle in contracting the ring to exert a substantial pressure thereagainst, said member having a rounded cam-like portion to engage said cover.

4. A clamping device for removably securing a cover upon a barrel, said device comprising a split channeled ring, inwardly extending lugs adjacent the ends of the ring, and means for contracting and expanding the ring, said means including a link pivoted at one end to one of said lugs, a second link pivoted at one end to the other of said lugs, an operating member pivotally connected adjacent its inner end with the other end of the first named link, said other end of the second link having pivotal connection with another portion of the operating member, whereby upon rotation of the said member to full ring contracted position to clamp the cover on the barrel, the pivot points of the links will be positioned with reference to the operating member tending to retain the ring in contracted position.

5. A clamping device for removably securing a cover upon a barrel, said device comprising a split channeled ring, inwardly extending lugs adjacent the ends of the ring, and means for contracting and expanding the ring, said means including a link pivotally connected to and adjacent each end of the ring, and a rotatable actuating member pivoted at points on opposite sides of its rotative center to the free ends of the respective links.

6. A clamping device for removably securing a cover upon a barrel, said device comprising a split channeled ring, inwardly extending lugs adjacent the ends of the ring, and means for contracting and expanding the ring, said means including a link pivotally connected to and adjacent each end of the ring, and a rotatable ac-

tuating member pivoted at points on opposite sides of its rotative center to the free ends of the respective links, one of said links being shaped to engage the cover of a receptacle in contracting the ring to exert a substantial lateral pressure thereagainst.

7. A clamping device for removably securing a cover upon a barrel, said device comprising a split channeled ring, inwardly extending lugs adjacent the ends of the ring, and means for contracting and expanding the ring, said means including a

link pivotally connected to and adjacent each end of the ring, and a rotatable actuating member pivoted at points on opposite sides of its rotative center to the free ends of the respective links, one of said links being shaped to engage the cover of a receptacle in contracting the ring to exert a substantial lateral pressure thereagainst, said link engageable with the cover having a camlike portion for such engagement. 5

WILLIAM LOCKHART.
